UNITED STATES PATENT OFFICE.

WILLIAM H. LOOMIS, OF ALAMEDA, CALIFORNIA.

HOSE-PATCH.

SPECIFICATION forming part of Letters Patent No. 358,618, dated March 1, 1887.

Application filed October 2, 1886. Serial No. 215,190. (No model.)

To all whom it may concern:

Be it known that I, WILLIAM H. LOOMIS, of Alameda, Alameda county, State of California, have invented an Improvement in 5 Hose-Patches; and I hereby declare the following to be a full, clear, and exact description of the same.

My invention relates to a device for repairing weak or broken places in hose or pipe.

10 It consists of a cylindrical flexible section of sufficient size to surround the hose or pipe to be mended, and an arrangement of tongues or buckles by which it is held at any desired degree of compression, and a means for closing or compressing it upon the part to be mended, 15 all of which will be more fully explained by reference to the accompanying drawings, in which—

Figure 1 shows one form of my device with 20 the edges separated and the key removed. Fig. 2 shows the device applied to a hose and the key in place. Fig. 3 shows a modification of the device for producing essentially the same result.

25 A is a sheet of flexible material, made of sufficient size to clasp around the hose or pipe which is to be repaired, and having one edge, *a*, folded back upon itself, so as to leave a small channel in the fold, as shown. Near this edge 30 are slots or openings B, of sufficient size to receive tongues C, which project from the opposite edge of the sheet in such relation with the slots that they may be introduced into them when the sheet has been folded around the 35 hose or pipe to be mended.

Small lugs or indentations *c* are made in each of the tongues C, so as to project inwardly, as shown.

40 The operation is as follows: The sheet of metal A, being long enough to cover any weak or fractured place in the hose or pipe, is folded around the latter at the point of breakage, so that the break is inclosed in the unbroken part of the sheet A, the meeting edges being brought 45 together as nearly opposite to the break as possible. The tongues C are then introduced into the slots B, and a wedge-shaped piece, D, is introduced from one end, so that one edge will fit or travel into the groove formed by the 50 turned-back edge *a* of the plate A', while the

other edge of the wedge-shaped piece engages with one or another of the rows of projecting lugs *c*, before described.

The position of the channel *a* with relation to the rows of inwardly-projecting lugs *c* is 55 such that when the wedge-shaped piece D is driven in so as to engage the channel and the lugs it will cause the projecting tongues C to be forced farther into the slots B, which are made for them, and will draw the sheet of metal 60 tightly around the hose, thus causing it to clamp the latter firmly, while leaving a perfectly smooth exterior surface, not liable to catch or tear anything with which it may come in contact. 65

The lugs *c* being made in rows at a short distance apart, it will be manifest that the wedge may be made to engage any row of lugs, depending on the size of the hose around which the clamp or sheet *a* is placed, and as the 70 point engages one of the series of rows when the wedge is driven through, it will engage all the lugs in that row, and will thus draw the clamp on as tight as may be desired.

In Fig. 3 I have shown a modification in 75 which the metal is cut away on three sides to form the slot B, and the short tongue thus formed is simply pressed inward, so that a sort of tongue projects into the slot from the side nearest the edge of the sheet A. The tongue 80 C in this case being provided with the same lugs *c*, as before shown, these lugs will engage with the inwardly-projecting tongues B' of the slots B, and will thus form a lock, holding the band tightly wherever it may be placed. In 85 order to draw this band closely about the hose, the edges *a* are turned backward between the tongues C, and outwardly-projecting lugs *d* are formed upon the sheet A and behind the slots or openings B. In this case the clamp or 90 wedge D has one edge turned under, so as to engage the lugs *d*, and the other edge has rows of inwardly-projecting lugs, which engage the outwardly-turned edges *a*, before described, and when driven upon the tube, which has 95 been formed by introducing the tongues C into the slot B, it will act to draw the parts together, clamping them firmly upon the interior of the hose or tube, and the small projecting lugs *c* in the tongues C will engage 100

with the edges of the inwardly-projecting plates B', thus holding the device at any desired point to which it may be drawn. This wedge-shaped clamp D is driven on from one end, and serves to draw the tube closely together. It may be then left in position, or may be taken off, leaving the clamp in place, and the projecting lug d and the turned-over edges a may be flattened down or otherwise prevented from projecting so as to be in the way.

Various modifications of this device may be used; but the principle involved, which lies in the small projecting lugs or tongues, either 15 row of which may engage so as to buckle or lock the clamp around various sizes of hose, is the feature of my invention.

Having described my invention, what I claim

as new, and desire to secure by Letters Patent, is—

The flexible cylindrical sheet or band surrounding the hose or pipe and having slots or openings made in one edge, and the tongues projecting from the opposite edge with the inwardly-projecting supplemental tongues or lugs c, in combination with the wedge-shaped piece which is driven from one end so as to engage the lugs, whereby the clamp is drawn together and compressed upon the hose, substantially as herein described.

In witness whereof I have hereunto set my hand.

W. H. LOOMIS.
